GARMENT HANGER

Jack M. Zuckerman, Elmhurst, N.Y., assignor to Yankee Plastics, Inc., New York, N.Y., a corporation of New York

Filed Dec. 12, 1961, Ser. No. 67,878

Term of patent 3½ years

(Cl. D80—8)

FIG. 1 is a front elevational view of the design of the garment hanger showing my new design, the rear being a mirror image of the front shown, and

FIG. 2 is a side view of FIG. 1.

I claim:

The ornamental design for a garment hanger, substantially as shown and described.
